UNITED STATES PATENT OFFICE.

WILLIAM H. DOANE, OF CINCINNATI, OHIO.

TENONING-MACHINE.

SPECIFICATION forming part of Letters Patent No. 248,412, dated October 18, 1881.

Application filed February 10, 1881. (No model.)

To all whom it may concern:

Be it known that I, WILLIAM H. DOANE, a citizen of the United States, residing at Cincinnati, in the county of Hamilton and State of Ohio, have invented certain new and useful Improvements in Tenouing-Machines; and that I do hereby declare the following to be a full, clear, and exact description of the invention, such as will enable others skilled in the art to 5 which it appertains to make and use the same, reference being had to the accompanying drawings, and to the letters or figures of reference marked thereon, which form a part of this specification.

15 This invention relates to machines more especially designed for cutting tenons on heavy sticks of timber, either single tenons or double tenons.

The main object of my improvement is to 20 extend the utility of machines of this kind by such a construction thereof that they may also be used for cutting gains in sticks of timber at any distance from the ends of the stick.

To this end the main feature of my invention 25 consists in constructing the column of the machine on which the cutter-heads are mounted with a goose-neck, whereby a deep gap is formed across the column, through which gap the stick of timber may extend endwise and 30 be fed crosswise past the cutter-heads to be gained.

It further consists of certain novel mechanical combinations, clearly stated in claims at 35 the close of this specification, and relating to the disposition of the several cutter-heads, and the means for adjusting the same to the mode of belting the horizontal cutter-heads, and to the feed mechanism.

In order that my invention may be clearly 40 understood I have illustrated in the annexed drawings, and will proceed to describe a form thereof which has been embodied in practical working machines, with the understanding that the details of construction may be greatly 45 varied to suit circumstances or the views of builders or users without departing from the general features of my invention, which some of the claims at the close of this specification are intended to cover broadly enough to sub- 50 ordinate machines so varied or modified in details.

Figure 1 is a perspective view of my improved tenoning-machine, showing a stick of timber with a double tenon cut on one end of it. Fig. 2 is a plan view of the same. Fig. 3 55 is a vertical section in the plane indicated by broken line x x on Fig. 2. Fig. 4 is a vertical section in the plane indicated by broken line y y on Fig. 2. Figs. 5 and 6 are detail views of parts of the machine.

60 The same letters refer to similar parts in all the figures.

The column A is hollow and formed with a goose-neck, A', whereby a deep rearwardly-extending gap, A², is formed across the front 65 side of the column. The lower horizontally-disposed cutter-head B is secured on one overhung end of shaft B', the other overhung end of which carries the pulley B², through which it is driven. Shaft B' is mounted in bearings 70 on the vertically-movable slide B³, which is gibbed on a forwardly-projecting hollow bracket, A³, of column A. The lower end of slide B³ is connected to hanger C, which supports the slide and its adjuncts through the intervention of a screw, C', tapped in the hanger, and swiveled with its shank to a lug on the slide, as best seen in Fig. 4.

75 The lower end of the shank of the screw C' is provided with a hand-wheel, C², by turning 80 which the slide B³ may be moved up or down for the purpose of vertically adjusting cutter-head B.

The hanger C is suspended under bracket A³ on a screw, D, the shank of which is swiveled on the bottom wall of said bracket, and extending up into it has a bevel-wheel, D', keyed on its upper end, by which said screw D may be turned, on doing which the hanger C will be moved up or down, as the case may 90 be, carrying with it the slide B³ and all its adjuncts. Thus it will be seen that the cutter-head B may be vertically adjusted in two ways—either by the screw C or by the screw D.

95 The upper horizontally-disposed cutter-head, E, is secured on one overhung end of a shaft, E', on the other overhung end of which is secured a pulley, E², for driving it. Shaft E' is mounted in bearings formed or secured on a horizontally-movable plate or cross-slide, E³, 100 gibbed on a vertically-movable slide, E⁴, in turn gibbed on the standards A⁵ on the for-

ward end of the goose-neck A' of column A. It is preferable to arrange the axis of the shaft E' in the same vertical plane in which the axis of shaft B' lies.

5 The cross-slide E³ is controlled by a screw, E⁶, by operating which the cross-slide may be moved horizontally, so as to adjust cutter-head E, in order that it may cut one side of a tenon equaling or differing from the length of 10 one side of the tenon cut by the cutter-head B. Thus in cutting a single tenon both cutter-heads cut to the same line from the end of the stick. They also cut to the same line from the end of the stick when two tenons of equal 15 length are to be cut thereon. But when in cutting two tenons on the end of the stick one of the tenons is to be longer than the other, then the upper cutter-head E is adjusted to cut either beyond the line of the cut of the 20 lower cutter-head, B, or to a line nearer to the end of the stick, according as the upper or the lower tenon is to be the longer.

The slide E⁴ is supported on the hanger F through the intervention of a screw, F', tapped 25 in the hanger and swiveled to an ear on the slide. The screw is provided with a hand-wheel for operating it. By turning the screw the slide E⁴ may be vertically adjusted with respect to the hanger F. This hanger is supported 30 on a screw, F², the shank of which, being swiveled in the upper wall of hollow goose-neck A', passes into the same and carries at its lower end a bevel-wheel, F³, for turning it. By operating this screw F² the hanger F may 35 be adjusted up and down for the purpose of raising or lowering slide E⁴ with its adjuncts, one of which is the cutter-head E. Thus the cutter-head E may, like cutter-head B, be vertically adjusted in two ways, either by screw 40 F' or by screw F².

For the purpose of adjusting the slides B³ and E⁴ either separately or together, I provide the leading-shaft G, arranged in the hollow column, with one end projecting through the bracket A³ of such column, and through a vertical slot in slide B³, to receive a hand-wheel, G², for operating it. This leading-shaft is connected by a train of bevel-gearing to a parallel adjusting-shaft, H, arranged in the hollow goose-neck, 45 as clearly shown in Fig. 4. The leading-shaft G carries a bevel-wheel, G', adapted to mesh with and drive bevel-wheel D' on adjusting-screw D. The parallel counter-shaft H similarly carries a bevel-wheel, H', adapted to mesh 50 with and drive bevel-wheel F³ on adjusting-screw F². Bevel-wheel G', being shiftably connected by a spline to the leading-shaft, may be thrown out of and in gear with bevel-wheel D' by a shifter, G³, fixed on a cross rock-shaft or 55 stud, G⁴, one end of which protrudes through the outside walls of the column and carries a handle, G⁵, in order that it may be conveniently operated. This handle may be provided with a spring-latch adapted to lock the handle, so 60 as to hold bevel-wheel G' either in gear or out of gear, as the case may be. Bevel-wheel H'

is in similar manner shiftably connected by a spline to adjusting-shaft H, and may be thrown out of and in gear with bevel-wheel F³ by a shifter, H², fixed on a cross rock-shaft or stud, H³, 70 which protrudes through the outside wall of the hollow goose-neck and carries a handle the same as stud G⁴, the handle being in like manner adapted to be locked to hold bevel H' either in gear or out of gear, as the case may be. 75

It will now be readily understood that the cutter-heads B and E can be vertically adjusted by the operation of the leading-shaft G either simultaneously or separately, according as both bevel wheels, G' and H', are in gear or only one 80 or the other of them is in gear at the time. The screws D and F² are so threaded that their simultaneous operation will cause the respective cutter-heads B and E to be moved in opposite directions. The described various possible 85 adjustments of the cutter-heads B and E, together with their primary setting on their respective shafts, provide for all contingencies occurring in the work of tenoning single or double. These cutter-heads being for tenoning, are provided 90 with edge-cutters b and e respectively, which cut in advance of the knives to form clean-cut shoulders for the tenon or tenons. For gaining purposes gainer-heads must be substituted for the tenoner-heads shown. 95

In order that the cutter-heads B and E may be driven by a single belt without obstructing the free passage of the stick of timber through the gap in the column and beyond the belt, I pass such driving-belt I² from the driving-pulley I', over the pulley B² of cutter-head B, then pass it under an idler, I⁴, from which it passes up again over an automatic belt-tightener pulley, I⁵, to return in a horizontal direction to a large idler, I³, from which it runs forward again in a horizontal direction to pass around pulley E² of cutter-head E, to finally return to the driving-pulley I'. The driving-belt is thus "gapped" to correspond with the gapped column. The driving-pulley I' is keyed 100 to the main shaft I, mounted in suitable bearings across the back of the column or goose-neck. Idler I³ turns on a stud projecting from the outside wall of the goose-neck, while idler I⁴ turns on a stud projecting from slide B³. 115

The belt-tightener pulley I⁵ serves to hold the belt I² at the proper tautness under all adjustments of the cutter-heads B and E, and is to that end mounted on a stud projecting from a standard, I⁶, gibbed upon a bracket, b', on the slide B³. The foot of said standard I⁶ is provided with rack-teeth on its under side, which teeth are engaged by a spur-wheel, I⁷, keyed to a shaft mounted on bracket b', and carrying a sheave, I⁸, to which a rope or chain is fastened for the suspension of a weight, I⁹, from it. This weight, through the intervening devices, pulls constantly on the tightener-pulley. 120

The cutter-head K, used for cutting the central gap in forming a double tenon on a stick 130 of timber, is mounted on a vertical spindle, K', mounted in bearings on a vertical slide, K²,

gibbed on the inner side of the column some distance in rear of the cutter-heads B and E, but still having plenty of play in front of the end of the gap in the column. A vertical rack, 5 K³, is formed on the back of slide K², projecting through a slot into the hollow column and engaged by a spur-pinion, K⁴, on a shaft, K⁵, which is mounted in a hub, K⁶, projecting from the outer side of the column, and carries a hand- 10 wheel, K⁷, for operating it to adjust slide K² and the cutter-head K, supported thereby. This cutter-head K is arranged to cut to a line or point lying in or coincident with the outer plane of the edge-cutters of the non-adjustable 15 cutter-head B.

The lower end of the spindle K' carries a pulley, K⁸, which is driven by a belt from a pulley, L', on a counter-shaft, L, which carries another pulley, L², driven by a belt from a pul- 20 ley, L³, on the driving-shaft I of the machine.

The stick of timber to be operated on is supported on a carriage, M, provided with suitable adjustable knees m, for giving lateral support to the stick of timber, and the ordinary 25 clamp presser-foot M' at the forward end of the carriage, to securely hold the stick of timber down on the carriage near the point where it is subjected to the action of the cutters. The carriage is mounted on ways N' and N² of a 30 bench, N, which may be cast on the column, with a deep gap between the two. The carriage is traversed past the cutters by a leading-screw, O, which operates in a nut, O', connected to the carriage. At the front end the 35 leading-screw O is journaled in a bearing, n, at the front end of way N', the rear end of which terminates in a yoke, N³, in a bearing, n', in which the rear end of the leading-screw is journaled. This rear end of the leading- 40 screw carries an overhanging beveled friction-pulley, O², constructed with a beveled friction-surface, o, of large diameter, and another beveled friction-surface, o', of smaller diameter, concentric with the large one.

45 A cross-shaft, P, arranged in bearings of the yoke N³, in front of the friction-pulley O², is provided with a shiftable sleeve connected to it by a spline and provided with the beveled friction-pulleys p p', so arranged that the one 50 marked p may engage the friction-surface o, and the one marked p' the friction-surface o' of the friction-pulley O², on opposite sides of the axis of the latter. The distance between the beveled friction-pulleys p and p' is such 55 that both may be disengaged from the beveled friction-pulley O², and that only one of them at a time can be in gear with friction-pulley O². A collar, p², placed on the sleeve between the friction-pulleys p p', and provided with a 60 downwardly-projecting arm, is used for shifting such pulleys from the front of the machine through the intervention of a shifter-rod, P', a crank-arm, p³, of which operates on the arm of collar p² in any convenient or preferred way.

65 The front end of the shifter-rod is provided with a handle for turning it, and may be com-

bined with a spring locking device, P², adapted to lock the shifter-rod in any one of these three positions—namely: to hold both friction-pulleys p and p' out of gear, or to hold friction-pulley p in gear, or to hold friction-pulley p' in gear. 70

The shaft P, with its friction-pulleys, is driven by a pulley, P³, by means of a belt from pulley P⁴ on the counter-shaft L. To feed the 75 stick to the cutters the friction-pulley p is put in gear with friction-surface o of pulley O², producing a comparatively slow feed. After the stick has been duly operated on the friction-pulleys p and p' are shifted, so as to put 80 pulley p' in gear with friction-surface o' of pulley O², whereby a comparatively rapid return movement of the carriage M is effected. In order to obtain greater difference of speed 85 between the feed motion and the return motion by these friction-pulleys without unduly increasing the diameter of pulley O², the latter may be dished or made cup shape to some extent, as shown, so that the friction-surface o' thereof may lie in a plane back of the plane of 90 the friction-surface o. Such construction admits of an increase of the diameter of friction-pulley p' over that of pulley p, so that the speed of the return movement of the carriage will be augmented in consequence of the greater 95 peripheral speed of driver p', as well as of the reduced size of the driven friction-surface.

The nut O' may be only a half-nut arranged in a seat on the side of the carriage-sill and controlled by a hand-lever for causing it to engage or disengage screw O; and a means may be provided for effecting automatic engagement and disengagement of the screw by such half-nut. 100

From the foregoing description it will be 105 readily understood that a stick of timber may be gained crosswise at any distance from its ends by a suitable gainer head or heads, since the gapped column and gapped belt, for driving the cutter-head shafts B' and E', permit 110 the stick of timber to extend through the gaps of the column and belt and to be fed when so extended to the gainer head or heads.

Having thus described my invention, what I claim is—

1. In a tenoning-machine, the combination of 115 two adjustable parallel cutter-heads arranged on opposite sides of a gap in the frame or column and a carriage reciprocating in the direction of the depth of the said gap, substantially as before set forth.

2. In a tenoning-machine, the combination of 120 two adjustable parallel cutter-heads arranged on opposite sides of a gap in the frame or column a belt for driving the cutter-heads arranged over pulleys to leave a gap therein, and a carriage reciprocating in the direction of the depth of the said gap, substantially as before set forth.

3. In a tenoning machine, the combination of 125 two parallel cutter-heads arranged on opposite sides of a gap in the frame or column, and

a third cutter-head operating at right angles to and in rear of the first two, substantially as before set forth.

4. In a tenoning-machine, the combination of two parallel cutter-heads arranged on opposite sides of a gap in the frame or column, and a third cutter-head operating at right angles to and in rear of the first two and cutting to a line coincident with the outer plane of the edge-cutters of one of them, substantially as before set forth.

5. In a tenoning-machine, the combination of two adjustable parallel cutter-heads arranged on opposite sides of a gap in the frame or column, the arbor of one being endwise adjustable, a third cutter-head operating at right angles to the first two and cutting to a line coincident with the outer plane of the edge-cutters of the non-adjustable one of them, and a carriage reciprocating in the direction of the depth of the said gap, substantially as before set forth.

6. In a tenoning-machine, the combination of two parallel cutter-heads, the belt for driving them arranged over pulleys to leave a gap therein to correspond with the gap in the frame or column, and the automatic belt-tightener connected with the supporting-slide of one of said cutter-heads, substantially as before set forth.

7. In a tenoning-machine, the combination of the respective supporting-slides of the two parallel cutter-heads, the adjusting-screws, which support the slides by hangers, and a train of gears and shafts around the gap in the frame or column, with a leading-shaft and gear-shifters for turning either one or both of said adjusting-screws to adjust the cutter-heads separately or simultaneously, substantially as before set forth.

8. The combination of a cutter-head-supporting slide, a hanger supported on a power-driven adjusting-screw and guided on the slide, and a secon'l adjusting-screw between the hanger and the slide, for separate adjustment 45 of said slide, substantially as before set forth.

9. In a tenoning-machine, the combination of the respective supporting-slides for the two parallel cutter-heads, the hangers from which the slides are suspended, the adjusting-screws 50 between the respective hangers and slides, the adjusting-screws supporting the hangers, and a train of gearing with a leading-shaft and gear-shifters for turning either one or both of said adjusting screws to adjust the cutter-heads 55 separately or simultaneously, substantially as before set forth.

10. In a tenoning-machine, the combination of the respective supporting-slides of the two parallel cutter-heads, the adjusting-screws 6c which support the slides by hangers, and a train of gearing, including gear-shifters, and a leading-shaft arranged in the hollow column or frame, except that the leading-shaft protrudes for manipulation, substantially as before set forth.

11. The combination of the carriage, the nut thereon, the leading-screw, the driven bevel friction-pulley having two concentric friction-surfaces, and a pair of shiftable driving bevel 70 friction-pulleys mounted on a single shaft and arranged to engage the respective friction-surfaces of the driven pulley on opposite sides of its axis, substantially as before set forth.

In testimony whereof I affix my signature 75 in presence of two witnesses.

W. H. DOANE.
